D. CRAIG

ROOF VENTILATOR

Original Filed Feb. 13, 1919

Fig. 1

UNITED STATES PATENT OFFICE.

DAVID CRAIG, OF PEABODY, MASSACHUSETTS, ASSIGNOR OF ONE-HALF TO CHARLES H. LOVSEY, OF PITTSBURGH, PENNSYLVANIA.

ROOF VENTILATOR.

Original application filed February 13, 1919, Serial No. 276,790. Divided and this application filed August 9, 1922. Serial No. 580,630.

To all whom it may concern:

Be it known that I, DAVID CRAIG, a citizen of the United States of America, and resident of Peabody, in the county of Essex and State of Massachusetts, have invented new and useful Improvements in Roof Ventilators, of which the following is a specification.

This invention relates to a roof ventilator and more particularly to a roof ventilator for houses, garages, and other buildings adapted to be made in sections and set up by unskilled workmen, this being a division of my copending application, Serial No. 276,790, filed Feb. 13, 1919, patented, No. 1,427,943, Sept. 5, 1922.

The objects of the invention are to provide a roof ventilator of the type described which has improved ventilating means and apparatus by which the ventilating means may be controlled and adjusted at will, and in general to provide a roof ventilator which is superior to the ordinary type of ventilator.

Other objects of the invention will be apparent from the preferred embodiment of the invention illustrated in the accompanying drawings, in which:

Fig. 1 is a top plan of a portion of the roof, parts being broken away; and

Fig. 2 is a vertical sectional view of the central portion of the roof.

The particular embodiment of the invention shown for the purpose of illustration comprises in general a centerpiece CP, a plurality of hypotenuse or corner rafters H, a plurality of central rafters R sloping downwardly from the centerpiece between the hypotenuse rafters, a plurality of minor rafters M sloping outwardly from the hypotenuse rafters in parallelism with the center rafters, a king-post K extending downwardly from the centerpiece, and a plurality of roof sections S covering the spaces between the rafters.

The centerpiece CP is made hollow so that the roof may be ventilated therethrough and is preferably made cylindrical as illustrated. Ventilating openings are provided above and beneath the level of the roof either in

the ends or sides or in both the ends and the sides of the centerpiece.

In the drawings I have shown the centerpiece as being open throughout its entire upper end and as having a plurality of openings 1 in its lower end and a plurality of openings 2 in its peripheral wall beneath the roof. As shown in Fig. 1 the centerpiece is preferably provided with ridges 3 on the inside between the openings 1 and 2 to strengthen the same. The centerpiece is preferably provided with a hollow portion 4 into the lower end of which is threaded the tubular king-post K. A rod 5 extends through the tubular king-post K and the axial portion 4 of the centerpiece and on the upper end of this rod is mounted a disk 6 having a flared peripheral portion 7 to which is secured an annular band 8, the disk 6 preferably being of somewhat greater diameter than the centerpiece and the band 8 preferably extending to or below the level of the upper end of the centerpiece to serve as a cover for the upper end thereof. An ornamental weight 9 may be mounted on the upper end of the rod above the disk 6. To the lower end of the rod 5 is connected a lever 10 which is pivotally mounted on a collar 11 threaded upon the lower end of the king-post K, a pawl and ratchet mechanism 12 being provided to hold the lever in adjusted position. By adjusting the lever 10 the disk 6, which serves as a damper to control the effective size of the opening through the centerpiece may be raised or lowered to vary the rate of ventilation.

The hypotenuse rafters comprise a metallic plate 13 to each side of which is secured a wooden strip 15. The central rafters are formed in a similar manner in that they comprise a central metallic plate 16 and wooden strips 17 secured to the side of the center plate.

The hypotenuse rafters and the central rafters are secured to the centerpiece by means of T-shaped lugs 20 the lateral portions of which fit along the centerpiece and the longitudinal portions of which extend outwardly along the metallic plates of the rafters as illustrated in Fig. 1.

The outer ends of the rafters are connected to the lower end of the king-post K by means of tie-beams 23 which are connected to the king-post through the mechanism of turn-buckles 24 and clevises 25 which fit over and are pivoted to a collar 26 on the lower end of the king-post. The collar is threaded on the king-post K so that it may be vertically adjusted along the king-post before the tie-beams are connected thereto. The collar 26 is provided with vertical flanges 27 to which braces 28 may be connected, the braces being connected at their opposite ends to the hypotenuse and central rafters intermediate the ends of the rafters.

After the roof sections have been put in place, battens 33 are placed over the central rafters so as to overlap the roof sections and the parts are secured together by suitable bolts. The central metallic plate 13 of the hypotenuse rafters extends somewhat above the level of the boards 30 forming the upper surface of the roof sections S, viz, a distance equal to the thickness of the battens of the minor rafters, and on both sides of the upstanding portions of the plates 13 are mounted filling strips 37. Over the filling strips 37 is mounted a batten 38 which is Y-shaped in cross section and which extends outwardly beyond the filling strips 37.

After the roof sections and battens have been secured in position a lead flashing F is fitted around the centerpiece and over the portions of the roof sections and battens immediately surrounding the centerpiece. The flashing F is folded inwardly over the upper edge of the centerpiece at its upper end and at its lower end the flashing is fitted over hypotenuse battens 38.

From the above it is apparent that the ventilating apparatus for the roof is built into or arranged to form an essential portion of the frame of the roof structure, that means are provided in a convenient position for positively controlling the ventilating apparatus, that the roof is effectively sealed against leakage when the ventilator is closed, and that by virtue of the features of construction herein disclosed all of the aforesaid objects are attained, as well as other advantages which will be obvious to those skilled in the art.

I claim:

1. In roof construction the combination with a cup-like metal member open at the top, of hypotenuse rafters having flange portions fitting around the upper portion of the cup, said cup having lateral ventilation apertures formed therein immediately beneath the point of engagement by the rafters, whereby the cup member provides a connecting support for the rafters, and a central

ventilation outlet communicating with the 65 normally dead air space immediately beneath the rafters.

2. In roof construction a central cup-like member, hypotenuse rafters having end portions terminally engaging the sides of the 70 cup intermediate the height thereof, a hollow king-post secured to and depending from the cup, tie beams connecting the king-post and rafters, the cup member being open at the top and having apertures formed therein beneath the point of engagement of the hypotenuse rafters therewith, a cover member for the cup, and control means carried by the hollow king-post and operating through said post to regulate the position of the 80 cover.

3. A center-piece for sectional buildings comprising a tubular member and a center projection within said member, braces connecting the tubular member and projection forming sector-like compartments, said compartments being open at the top and at the lower portion, and the tubular member having rafter engaging portions above said lower open portion, whereby the tubular member serves both as a braced rafter connection and a ventilator from the space below to the space above the rafters. 96

4. A center-piece for sectional buildings comprising a tubular member and a center projection within said member, braces connecting the tubular member and projection forming sector-like compartments, said compartments being open at the top and at the lower portion, and the tubular member having rafter engaging portions above said lower open portion whereby the tubular member serves both as a braced rafter connection and a ventilator from the space below to the space above the rafters, the projection being hollow, and draft controlling means supported by the tubular member and controllable through said hollow projection. 100

5. In roof construction a tubular centerpiece, brace members projecting inwardly 110 from the tubular member, rafters having their termini engaging the exterior of the tubular member adjacent said braced portions thereof, the tubular member having ventilation apertures formed therein below 115 the point of engagement by the rafters, a cover for the tubular member of greater diameter than such member, said cover having a depending peripheral flange portion, means on the tubular member for supporting said cover, and means for variably adjusting the position of the cover as respects the tubular member. 120

6. In roof construction, a roof comprising rafters a center-piece of tubular form having a base portion at one end, the base portion having a hollow upward extension within the tubular member, and a depending king-

post receiving boss, a king-post carried thereby, the lower portion of the tubular member and the base having ventilation apertures formed therein, and the upper portion being continuous to provide a center-piece bracingly engaging the termini of said rafters, means overlapping the upper end of

the tubular member for controlling the draft therethrough, and regulating means therefor adjustably supported by the king-post and projecting upwardly through said post.

Signed by me at Boston, Mass., this 2nd day of August, 1922.

DAVID CRAIG.
